UNITED STATES PATENT OFFICE

2,448,945

COMBINED MAILBOX AND ILLUMINATED SIGN

Erhard Zacharias, New York, N. Y., assignor to
Postal Advertising Corporation, New York,
N. Y., a corporation of New York

Application June 22, 1944, Serial No. 541,530

2 Claims. (Cl. 40—132)

1

This invention relates to an advertising device combined with a depository cabinet having particular reference to a structure which is suitable in design and utility features to be located in a public place, as on the public sidewalk in a city, e. g., a postal letter box, and more particularly to a construction providing exchangeable advertising means at the outside of the device.

In most of the structures of this type hitherto known a box-like hood is attached to the top of the letter box, said hood carrying all the advertising means to be combined with the letter box.

It is an object of this invention to use not only the space above the letter box for advertising purposes but also the space adjacent to the side walls.

Another object of the invention is to provide compartments adjacent to the top and side walls at the outside of the letter box, adapted to receive exchangeable transparent or translucent panels showing advertisements, and illuminated by illuminating means placed in these compartments.

It is a further object of the invention to construct the combined advertising device and letter box as a single unit in which the carrier of the advertising means and the letter box are made of one piece simplifying thereby the manufacture and reducing the dimensions of the device to a minimum.

The foregoing and other objects of the invention will be apparent from the following description of an embodiment thereof illustrated in the accompanying drawings in which:

Fig. 1 is a perspective view of the letter box provided with the advertising device according to the invention;

Fig. 2 is a front view, partly in section of a unit constructed according to the invention, and

Fig. 3 is a horizontal section taken on the line 3—3 of Fig. 2.

Referring to the drawings, 1 is a letter box of usual construction, 2 is a door provided in the front wall, and 3 an opening in the front wall of the letter box for the introduction of letters or other matters to be mailed.

The side walls of the letter box 1 are provided at their outside with extensions 4, said extensions forming frames 5 which are parallel to the side walls of the letter box. Grooves 6 in the vertical members of said frames serve as guides for transparent or translucent panels 7 which show the advertisements and which are inserted and removed on top of the frames.

The upper wall of the letter box 1 is also pro-

vided with extensions 8, forming frames 9 above and parallel to the front wall of the letter box, and having guideways 10 for panels 11 removably inserted on the front and above the letter box.

5 Similar frames may be provided at the back of the letter box.

The extensions 4, 8, frames 5, 9, and panels 7, 11 constitute compartments 12, 13 adjacent to the side walls and on the top of the letter box.

10 Said compartments are open at the top and covered by a detachable hood 14. Within the compartments 12, 13 illuminating means, such as incandescent lamps or neon tubes 15 are provided whereby the advertisements on the panels can be 15 made clearly visible during the night.

The compartments 12, 13 may also be used for the arrangement of any optical or acoustical devices, such as talking machines or television devices, projecting pictures on the panels 7, 11 or 20 emitting sound waves which may pass through holes 16 provided in said panels.

25 The hood 14 is composed of a central part 17 and exterior parts 18 articulated at said central part by hinges 19. The exterior parts 18 are arranged in the path of the removable panels 7, 11, and present doors which allow the access to the panels and the exchange of the same when turned upwardly. Therefore, the panels may be removed from or inserted into the frames without

30 removing the hood 14. The parts 18 are held in closing position by bolts 20 which are rotatably mounted at the inside of the hood 14 around an axis normal to the surface of said hood. Any well known locking device having a key hole (indicated at 21) leading to the outside of the hood may be provided to rotate the bolts 20 parallel to the surface of the hood and to allow thereby the opening movement of the parts 18.

35 The letter box 1, the extensions 4, 8, and the frames 5, 9 constitute a unit consisting of a single piece the manufacture of which is relatively inexpensive, and permits the use of a maximum of advertising panels within a relatively small space as well as the arrangement of a relatively great 45 number of different devices in the compartments within said unit.

The construction of the letter box may further 40 be improved by the provision of a safety device protecting the content of the letter box from theft. This device consists of needles 22 the heads of which are mounted on a rod 23 fixed at the inside of the letter box 1 along the upper border of the opening 3 for the introduction of letters or the like. The length of the needles 22 45 is greater than the distance between the upper

and lower border of the opening 3. The needles 22 may freely swing around the rod 23 and form a curtain behind the opening 3 which threatens to wound anybody who would try to penetrate with his fingers through the opening 3.

While I have shown and described a preferred embodiment of my invention, I do not wish to be understood as limiting myself to the specific structure shown and described but intend to claim my invention as broadly as may be permitted by the state of the prior art and the scope of the appended claims.

I claim:

1. A combined postal mailbox and advertising device consisting of, first, a mailbox of usual shape, comprising a container for mail; second, compartments provided outside of said mailbox adjacent to the four side walls of the same; two of said compartments being formed partly by walls of the mailbox and partly by frames integral with said mailbox and formed by extensions projecting laterally and upwardly from two opposite side walls of the mailbox; third, of exchangeable advertising panels removably inserted in said compartments, said panels being preferably transparent to be illuminated by appropriate means placed in said compartments; fourth, a detachable hood covering the mailbox and all the compartments surrounding said mailbox, said hood being provided with doors, each of them situated in the path of one of the compartments carrying the exchangeable advertising panels, thereby permitting easy exchange of the same.

2. In the combined device as defined in claim 1, said detachable hood shaped like a pyramid, comprising a central part forming the top of the pyramid and exterior parts articulated at said central part, said exterior parts being arranged in the path of the compartments surrounding the mailbox and resting with their outer borders on the upper borders of said compartments forming doors and giving access to the panels arranged in the compartments when turned upwardly.

ERHARD ZACHARIAS.
